WRINGER

Walter L. Kauffman, II, Erie, Pa., assignor to
 Lovell Manufacturing Company, Erie, Pa., a
 corporation of Pennsylvania

Application March 17, 1937, Serial No. 131,339

8 Claims. (Cl. 68—263)

Power wringers are commonly provided with a release device and some means for resetting the pressure on the wringer for further operations. The present invention is designed to improve and 5 simplify release and resetting mechanisms for wringers. Features and details of the invention will appear from the specification and claims.

Preferred embodiments of the invention are illustrated in the accompanying drawings as 10 follows:

Fig. 1 shows a front elevation of the wringer partly in section.

Fig. 2 a plan view of the wringer.

Fig. 3 a central vertical section on the line 3—3 15 in Fig. 2.

Fig. 4 an elevation of the releasing and resetting mechanisms in released position.

Fig. 5 a perspective view of one of the links of 20 the releasing mechanism.

Fig. 6 a plan view of the releasing rod in released position.

Fig. 7 a front elevation partly in section of an alternative construction.

Fig. 8 a plan view of the modification shown in 25 Fig. 7.

Fig. 9 an elevation showing the parts in released position.

Fig. 10 an elevation of an end of a wringer 30 showing a further modification.

In the structures illustrated in Figs. 1 to 9 the following parts are in common:

1 marks a base of the wringer, 2 and 3 side stiles. A lower roll 4 has a shaft 5, and an upper roll 6 has a shaft 7. The shaft 5 is journaled in 35 bearings 8. The bearings 8 are mounted on brackets 9 in the side stiles. The upper shaft 7 is journaled in bearings 10 slidingly mounted in the upper ends of the side stiles. A spring 11 rests on the bearings 10 and is adjusted by a screw 12 40 operating in a fitting 13 on a top bar 14.

The top bar is detachably secured at one end by interlocking shoulders 15 and 16 struck up from the end of the top bar and the side stile 45 respectively.

The opposite or release end of the top bar is provided with a resetting and release device. This comprises a toggle lever 17, the toggle lever having a link 18 which is of channel form and is 50 pivotally secured to the top bar by a bolt 19 extending through the side walls of the link and the top bar. A link 20 of the toggle lever is also of channel form and is pivotally connected with the link 18 by a pin 21. The sides of the link 20 straddle the side stile 2, and the link is

pivotedly connected to the side stile by pin 22. When the toggle lever is depressed it forces the release end of the top bar down into set position and puts pressure on the spring. The screw may 5 adjust the amount of pressure but the top bar is normally used for ordinary resetting. The pivots of the toggle lever are out of alignment when in set position as clearly shown in Figs. 1 to 9 so that the toggle lever is in an unstable 10 condition, that is to say, unless restrained or held in its set position the arrangement of these pivots will result in the breaking of the toggle and the release of the top bar.

The link 18 has a projection 24 with a cam surface. This cam surface engages a beveled end 25 on a pin 25a. The pin 25a is slidingly mounted in an ear 26 secured to the top bar. The upper end of the pin 25a has a beveled or cone surface 27 which engages an opposing cone surface 28 on 20 an operating bar 29. These cone surfaces are yieldingly held in alignment by coil springs 30, the ends of which engage the pin 25a and the rod 29. The rod 29 has its opposite end beveled at 31 and the beveled end 31 engages a beveled end 25 32 of a rod 33. The rod 33 is slidingly mounted in an ear 33a on the top bar. The rods 29 and 33 are yieldingly held in alignment by a spring 34 which overlaps these rods at each side of the beveled surfaces 31 and 32. The end of the rod 30 33 is secured to a lever 35. The lever 35 is pivotally mounted by a pin 36 on an ear 37 arranged on the end of the top bar. The opposite end of the lever 35 is secured to the rod 38, and is slidingly mounted in an ear 39 extending from the 35 top bar. The rod 38 is provided with a beveled end 38a which engages a beveled end 40 of an operating rod 41. The ends of the rods 33 and 41 are yieldingly held in alignment by a spring 42 overlapping the ends of these rods. The opposite 40 end of the rod 41 has a beveled end 43 engaging a beveled end 44 of a rod 44a. The rod 44a is fixed in an ear 45 extending from the top bar. A spring 46 overlaps the ends of the rods 44a and 41, holding the beveled ends in register. 45

In the operation of the device should the rod 29 be struck it moves the beveled surfaces 28 or 31 or both out of register with the opposing beveled surface and this permits the rod 25a to retract under the camming action of the projection 24 acting through the outward pressure on the links due to their unstable arrangement and this releases one end of the top bar. The interlocking shoulders are preferably such that when the top bar swings up at the release end 55

these interlocking shoulders also release, thus giving full release to the rolls. Should the rod 41 be struck the beveled surfaces 48 or 49, or both beveled surfaces, may be moved out of register 5 with the beveled surfaces engaged thereby and this permits of an endwise movement of the rod 38 and this movement is communicated through the lever 35 to the rod 33 which permits the retracting movement of the rod or bar 38 and rod 25a so as to permit a release movement. After 10 a release it is only necessary to engage the interlocking shoulders 15 and 16 and to force down the toggle lever to set position. During this downward movement of the toggle lever it is necessary 15 to move either the operating bar 28 or the bar 41 so as to permit a retracting movement of the rod 25a to permit the projecting end 24 to move into position. The conical end 25 engaging the upper surface of the projection retracts the rod 20 25a, permitting of this upward movement.

In the construction shown in Figs. 7, 8 and 9, the parts are similar except a retaining bolt 41 engages the projection 24. This bolt is slidably mounted in an ear 48 arranged on the frame. 25 The bolt has a reduced shank 47a. A spring 48a is arranged in the ear around the shank and operates against the shoulder 49, at the end of the bolt. The spring therefore yieldingly forces the bolt into position to restrain the link 18. The 30 end of the shank 47a is provided with a ferrule 50 in which a cord 51 is secured. The cord 51 extends around a grooved lever 52. This grooved lever is pivoted on a pin 53 which is mounted in an ear 54 on the end of the cross bar. The cord 35 extends around the lever and is secured by a ferrule 55 with a screw 56. The screw operates in an ear 57. In operation when it is desired to effect a release the cord 51 is struck on either side of the wringer and this deflection of the cord 40 retracts the bolt or latch 41 thus permitting a release of the toggle lever and the release of the pressure.

In Fig. 10 the toggle lever pivots are in alignment to form a stable relation so that when the 45 toggle lever is set it remains in set position until moved past the neutral or central point of these pivots to break the toggle. In this structure the link 28 has the projection 58 with a cam surface 59. A cam block 60 engages the camming surface 59. The cam block is carried by a pin 61 similar to the pin or shank 47a, and the cord 51 operates in a manner similar to that shown in Figs. 7 to 9. When the cord is deflected it retracts the cam block 60 and this operating on 55 the projection 58 forces the toggle lever outwardly so as to carry the pivots past the neutral point, thus breaking the toggle lever and effecting a release.

What I claim as new is:

60 1. In a wringer, the combination of a frame; rolls mounted in the frame; a pressure means exerting pressure on the rolls; release devices operating on the pressure means for releasing the pressure thereof comprising an operating bar extending lengthwise of the wringer and having a beveled end; an endwise movable tripping member, said member having a beveled end opposing the beveled end of the operating bar; yielding means retaining said bar and member in register, the off-setting of the beveled ends operating to effect a release of the release devices; and an auxiliary member mounted on the opposite side of the wringer having operative connection with the operating bar.

75 2. In a wringer having a frame, rolls mounted

in the frame, a pressure means exerting pressure on the rolls, and release devices operating on the pressure means for releasing the pressure thereof comprising; the combination with said release devices of a trip mechanism having a contractile 5 mechanism operating to effect the operation of the release devices through its contraction, said trip mechanism having an operating bar having a beveled end, and a member having a beveled end opposing the beveled end of the bar, and a yieldable means retaining the bar and member in register and permitting the off-setting of the beveled end of the bar operating to effect a release of the release devices.

3. In a wringer having a frame, rolls mounted 15 in the frame, a pressure means exerting pressure on the rolls, and release devices operating on the pressure means for releasing the pressure thereof; the combination with said release devices of an operating bar normally restrained from axial 20 motion having a beveled end; an endwise movable tripping member, said member having a beveled end opposing the beveled end of the operating bar; and yielding means retaining said bar and member in register, the off-setting of 25 the beveled ends operating to effect a release of the release devices.

4. In a wringer having a frame comprising a base and side stiles, a releasable top bar mounted on the stiles, rolls mounted in the frame, a pressure means exerting pressure on the rolls, and release devices; the combination with the release devices thereof, a normally stationary operating bar normally restrained from axial motion mounted on the top bar and having a beveled 30 end; an endwise movable tripping member, said member having a beveled end opposing the beveled end of the operating bar; and yielding means retaining said bar and member in register, the off-setting of the beveled ends operating to effect a release of the release device.

5. In a wringer having a frame, rolls mounted in the frame, a pressure means exerting pressure on the rolls, and release devices for releasing the pressure of the pressure means; the combination 45 with said release devices of a contractile means extending lengthwise of the wringer at one side thereof, said contractile means operating to effect, through the contraction thereof the release devices; and a means mounted on the opposite 50 side of the wringer operatively connected with the contractile means to effect a release.

6. In a wringer having a frame, rolls mounted in the frame, a pressure means exerting pressure on the rolls, release devices for releasing the 55 pressure of the pressure means; the combination with said release devices of a contractile means contracting through side deflection and extending lengthwise of the wringer at one side thereof, said contractile means actuating through the 60 contraction thereof the release devices; and means mounted on the opposite side of the wringer operatively connected with the contractile means to effect a release.

7. In a wringer having a frame, rolls mounted 65 in the frame, a pressure means exerting pressure on the rolls, and release devices for releasing the pressure of the pressure means; the combination with said release devices of a contractile means extending lengthwise of the wringer at one side 70 thereof, said contractile means actuating the release device through the contraction of the means; and a contractile means mounted on the opposite side of the wringer operatively connected with the contractile means to effect a release.

8. In a wringer having a wringer frame, rolls mounted in the frame, pressure means exerting pressure on the rolls, and release devices releasing the pressure of the pressure means; the combination with said release devices of a trip mechanism comprising a cord extending lengthwise of the wringer frame, said cord being contractible

by deflection of the cord, said cord operating to effect the operation of the release device through the contraction of the cord; and an auxiliary card, said cords being on opposite sides of the wringer and operatively connected. 5
